Inventor:

Reuben G. Holmes

UNITED STATES PATENT OFFICE.

REUBEN G. HOLMES, OF WORCESTER, MASSACHUSETTS.

IMPROVED CLOTHES-WRINGING MACHINE.

Specification forming part of Letters Patent No. **39,814**, dated September 8, 1863; antedated April 20, 1863.

To all whom it may concern:

Be it known that I, REUBEN G. HOLMES, of the city of Worcester, county of Worcester, and State of Massachusetts, have invented a new and useful Improvement in Clothes-Wringing Machines; and I do hereby declare that the following is a full and exact description thereof, reference being had to the accompanying drawings, and to the letters of reference marked thereon.

To enable others skilled in the art to make and use my invention, I will proceed to describe its construction and operation.

The letters A A represent two posts of the machine.

The letter B represents a top piece holding the posts firmly.

Letter C represents an iron shaft, which passes through the lower roller.

Letter E represents a crank attached firmly to the shaft C.

F represents the lower or stationary roller, and the letter G the upper or adjustable roller.

The letters H H represent two boxes, one at each end of roller G.

The letter I represents a cross-bar or follower, resting at each end of the machine on the boxes H H.

The letter J represents an india-rubber spring in the center and between the follower I and the lower spring, K.

The figures K and L represent two springs, placed horizontally one above the other, and arranged in such a manner as to apply the pressure of the springs K and L to the boxes H H, through the middle of the length bar I.

The letter N represents a screw placed in the center of the top piece B, extending down to the top of spring L, and by means of which the pressure on the springs is adjusted and regulated.

I do not claim separately any of the above-described parts as herein shown irrespective of their particular application and arrangement herein shown; but

What I do claim as my invention, and for which I desire to secure Letters Patent, is—

The arrangement of the springs K and L, so arranged as to bear upon the center of the bar I, thereby producing a greater and more equal pressure.

R. G. HOLMES.
